UNITED STATES PATENT OFFICE

121,461

DESIGN FOR A LAWN OR PORCH GLIDER

Carroll C. Tabb, Shreveport, La., assignor to
Frostbrand Furniture Mfg. Co., Shreveport,
La., a corporation of Louisiana

Application June 20, 1940, Serial No. 93,148

Term of patent 14 years

To all whom it may concern:

Be it known that I, Carroll C. Tabb, a citizen of the United States, residing at Shreveport, in the parish of Caddo and State of Louisiana, have invented a new, original and ornamental Design for a Lawn or Porch Glider, of which the following is a specification, reference being made to the accompanying drawing forming a part thereof in which

Fig. 1 is a perspective view of a lawn or porch glider embodying my new design;
Fig. 2 is an end elevational view thereof; and
Fig. 3 is a rear elevational view of the same.

This application is a continuation-in-part of applicant's copending application, Serial No. D-85,788, filed June 30, 1939, for a design for a lawn or porch glider.

The lawn or porch glider of my design is characterized by the end frame portions.

I claim:

The ornamental design for a lawn or porch glider, substantially as shown and described.

CARROLL C. TABB.
